Assistant Examiner — Ieisha N Price

(74) Attorney, Agent, or Firm — Boyle Fredrickson, S.C.

(57) **CLAIM**

The ornamental design for a positioning clip, as shown and described.

DESCRIPTION

FIG. 1 is a top isometric view of a positioning clip incorporating my new design, the dotted lines forming no part of the claimed design;

FIG. 2 is a front elevation view thereof, the rear elevation view being a mirror image thereof;

FIG. 3 is a right side elevation view thereof, the left side elevation view being a mirror image thereof;

FIG. 4 is a bottom plan view thereof;

FIG. 5 is a top plan view thereof; and,

FIG. 6 is a bottom isometric view thereof.

1 Claim, 6 Drawing Sheets(56)
